UNITED STATES PATENT OFFICE

116,625

DESIGN FOR A FEED HOPPER FOR DOUGH MOLDING MACHINES

Edward T. Parsons, Upper Montclair, N. J., as-
signer to Thomson Machine Company, Belle-
ville, N. J., a corporation of New Jersey

Application June 13, 1939, Serial No. 85,471

Term of patent 14 years

To all whom it may concern:

Be it known that I, Edward T. Parsons, a citizen of the United States, and a resident of Upper Montclair, in the county of Essex and State of New Jersey, have invented a new, original, and ornamental Design for a Feed Hopper for Dough Molding Machines, of which the following is a specification, reference being had to the accompanying drawing, forming part thereof.

Figure 1 is a perspective view of a feed hopper for dough molding machines showing my new design.

Figure 2 is a rear elevational view of the feed hopper on a reduced scale.

Figure 3 is a front elevational view of the feed hopper, on a reduced scale, and

Figure 4 is an elevational view of the end of the feed hopper opposite that shown in Figure 1, on a reduced scale.

I claim:

The ornamental design for a feed hopper for dough molding machines, substantially as shown and described.

EDWARD T. PARSONS.
